THERMOCOMPRESSOR

John F. Plummer, Jr., Phillipsburg, N. J., assignor
to Ingersoll-Rand Company, New York, N. Y.,
a corporation of New Jersey

Application March 18, 1948, Serial No. 15,681

4 Claims. (Cl. 230—95)

1

This invention relates to thermo-compressors of the steam ejector type which are adapted to develop relatively high vacuum pressures.

Ejectors of the type to which this invention appertains are normally used in the first few stages of a thermo-compressor system in which a plurality of steam ejectors are connected in series, i. e. with each ejector discharging into the succeeding ejector. In such a system at least the first stage ejector operates at or below the freezing pressure of water, namely 4.5 mm. of mercury. At this pressure any moisture entrained in the propelling steam will condense and freeze at the ejector nozzle tip and on the surface of the diffusor passage, thereby causing erratic operation of the ejector and in some instances complete loss of the inlet pressure.

In order to obviate this difficulty the practice has been to either warm the nozzle body and the throat portion of the diffusor by some external means, such as steam coils or electrical heating devices, or to superheat the energizing steam immediately before it enters the ejector nozzle. Although these practices are to a great extent satisfactory, there are, however, inherent disadvantages and limitations associated with these methods. For example, in either method an auxiliary source of heat or power is necessary and in the latter method, though effective in preventing the formation of ice on the nozzle surface, it does not always prevent the formation of ice on the inner surface of the diffusor.

In the present invention the icing problem is solved in a simple and highly efficient manner by utilizing characteristics inherent in the operation of a steam ejector. During the operation of a steam ejector, there is a temperature differential between the inlet and discharge ends of the nozzle and of the diffusor due to the change in pressure of the fluids flowing therethrough. The magnitudes of these temperature differentials are, of course, dependent on the amount of pressure drop, in the first case, or pressure rise, in the latter instance, of the fluids. In any case there is a flow of heat in the material surrounding the fluid being expanded or compressed. Thus, by providing a flow path of sufficient area in these materials, an adequate amount of heat is conducted, in the one case, from the inlet or warmer end portion of the nozzle to the nozzle tip to prevent the formation of ice thereon, and in the other case from the outlet end portion of the diffusor to the icing zone, i. e. the zone or portion of the inlet end of the diffusor where experiments have shown that particles of ice are most likely to adhere.

2

It is accordingly one object of my invention to prevent the formation of ice on surface areas of steam ejectors by utilizing a portion of the heat which is normally radiated to the atmosphere from the energizing steam.

Another object of my invention is to conduct a portion of the heat available in the fluid discharged from an ejector to the inlet end portion of the diffusor.

A further object of my invention is to conduct heat from the inlet end of an ejector nozzle to the discharge end thereof.

Other objects will be in part obvious and in part pointed out hereinafter.

15 In the drawings accompanying this specification and in which similar reference numerals refer to similar parts,

Figure 1 is a longitudinal view, in section, of a steam ejector constructed in accordance with the practice of the invention.

Figure 2 is a similar view of a steam ejector embodying an alternate construction of the present invention, and

Figure 3 is a transverse view taken through 25 Figure 2 on the line 3—3.

Referring to the drawings and more particularly to Figure 1, 10 designates, in general, a steam ejector having a non-icing nozzle unit 11 mounted on the inlet 12 of the ejector casing 13. Secured to the inlet 12 is a diffusor 14 which, in this instance, has a converging-diverging diffusor passage 15 with the converging or inlet section 16 being adjacent the inlet passage 17 in the inlet 12 for the fluid to be evacuated, whereas the diverging section 18 serves as a discharge passage 30 for the propelling steam and the evacuated fluid.

In order to conduct a portion of the heat available in the fluid flowing through the diverging section 18 to the icing zone 19 in the converging section 16, the diffusor is constructed so that the width of the diffusor passage 35

40 with this construction the portions of the casing wall having the maximum cross sectional area form the opposed end portions of the converging and diverging sections 16 and 18 and the restricted or throat section 20 therebetween. Since the rate of change in temperature along the diffusor is roughly constant, the rate of heat flow in the casing wall is directly proportional to the cross sectional area presented to such flow and the maximum flow of conducted heat will occur in said end portions and the section 20 of the diffusor casing and, therefore, a sufficient amount of heat will be conducted a relatively 45 short distance to the icing zone 19 from the re-

stricted and diverging sections 20 and 18, to prevent the formation of ice particles on the inner surface of the inlet section 16. This form of the invention also lends itself particularly to ease in fabrication and an exterior of uniform construction, due to the converging-diverging diffusor passage.

Icing of the discharge end or tip 21 of the nozzle 11 is prevented in a somewhat similar manner by constructing the inlet end or warmer portion 22 of the nozzle wall somewhat thicker than the discharge end. The actual thickness of the nozzle wall is, of course, dependent on the temperature differential between the inlet and discharge ends of the nozzle, and it is merely necessary to provide a flow path of sufficient area to permit a rate of heat transfer which will raise the temperature of the nozzle tip 21 to at least 32° F. In order to restrict the flow of conducted heat to a path along the nozzle and diffusor, they are encased by an insulating material 23.

In an alternate form of diffusor construction, shown in Figure 2, an ejector 24 of conventional type, that is, with a relatively thin walled diffusor, is provided with a non-icing nozzle unit 11 and the diffusor is encased by a jacket 25 which encircles the diffusor casing 26 and forms a fluid containing chamber 27 therewith. An opening 28 having a removable plug 29 therein, is provided at one end of the housing 25 so that the chamber 27 may be filled with water or any fluid of relatively good heat conducting characteristics to serve as a means for conducting heat from relatively warmer sections of the diffusor to a relatively cooler section, that is, from the sections 20 and 18 to the section 16.

In principle, the alternate form of the diffusor is similar to that of the first mentioned diffusor except, of course, in the latter case the thermal circulation of the fluid is the basis for the transfer of heat. However, it is to be understood that the thickness of the diffusor wall or depth of the chamber 27 required to prevent icing in the diffusor, is dependent on the thermal characteristics of the wall or the fluid, as the case may be, and the temperature differential which exists between the warmer and cooler portions of the nozzle or diffusor.

In any case, it is now obvious to those skilled in the art that the present invention provides a steam ejector which is capable of operating at or below the freezing pressure of water by utilizing a portion of the heat which was normally radiated to the atmosphere. Also, by virtue of its construction the efficient operation of the ejector under all conditions is entirely independent of any external source of heat or power other than the energizing fluid.

While I have shown and described one form

of my invention it is to be understood that various changes and modifications may be made therein without departing from the spirit of the invention as set forth in the appended claims.

5 I claim:

1. A steam ejector comprising a casing having an inlet and a diffusor, a steam nozzle adapted to said casing for discharging steam into the diffusor, and means for conducting heat from relatively warm portions of said diffusor to relatively cool portions, said means comprising a closed jacket encircling the diffusor and having a liquid therein.

2. In a steam ejector adapted to operate at or below the freezing pressure of water, a casing having an inlet and a diffusor, a water jacket encircling the diffusor, and a nozzle for discharging propelling steam into said diffusor, the wall of said nozzle being of sufficient thickness to conduct heat absorbed from steam flowing therethrough to the discharge end of said nozzle for preventing the formation of ice on the surface thereof.

3. In a steam ejector adapted to operate at very low absolute pressures, the combination of an ejector casing forming a converging-diverging diffusor passage, an ejector nozzle for discharging steam into the diffusor passage of the ejector casing, insulation on the external surfaces of the nozzle to force the flow of conductive heat outwardly toward the end of the nozzle, and external means on the ejector casing for inducing the conductive heat of the steam to flow from the diverging section of the ejector casing to the converging section.

4. In a steam ejector adapted to operate at very low absolute pressures, the combination of a casing forming a converging-diverging diffusor passage and having a wall of relatively great thickness so as to possess good thermal conduction properties, and a layer of suitable insulation around the outer periphery of the ejector casing covering the diverging section of the ejector casing and extending back to the converging section of the casing so as to force the conductive heat of the steam to flow from the diverging section of the casing to the converging section.
